UNITED STATES PATENT OFFICE.

ERNST H. CARLSON, OF CHICAGO, ILLINOIS, ASSIGNOR OF ONE-HALF TO ERNST EKMAN,
OF CHICAGO, ILLINOIS.

WIRE-TWISTING TOOL.

1,324,583.

Specification of Letters Patent. Patented Dec. 9, 1919.

Application filed March 10, 1917. Serial No. 153,838.

To all whom it may concern:

Be it known that I, ERNST H. CARLSON, a citizen of the United States of America, and a resident of Chicago, county of Cook, 5 and State of Illinois, have invented certain new and useful Improvements in Wire-Twisting Tools, of which the following is a specification.

The main objects of this invention are to 10 provide an improved form of tool or implement adapted for the twisting together of wires or the ends of a wire; to provide such a tool adapted to hold the free adjacent wire ends in spaced relation so that an even and 15 uniform twist may be secured; to provide a wire twisting tool which is simple in construction and rapid and efficient in operation; and to provide such a tool adapted especially for setting the stay wires in 20 concrete forms.

An illustrative embodiment of the invention is shown in the accompanying drawings, in which—

Figure 1 is a front view of the improved 25 wire twisting tool with a portion of one of the casing members broken away.

Fig. 2 is a view in perspective of the casing or supporting member with portions thereof broken away to show the interior 30 construction and mechanism housed therein.

Fig. 3 is a side view, partly in section, with parts thereof broken away.

Fig. 4 is a view showing how the improved tool is used for twisting wire.

Fig. 5 is a front view of another embodiment or modified form of my improved device.

Fig. 6 is a side view of the same, taken on the line A—A of Fig. 5.

Fig. 7 is a sectional detail taken on the line B—B of Fig. 5.

Fig. 8 is a detail in perspective of the wire holding member.

Fig. 9 is a view showing the improved 45 tool employed for another use.

This invention relates to a tool which is adapted to take the place of the ordinary pair of pliers for the twisting of wire, particularly where heavy, stiff wire is used. 50 The twisting of such wire with ordinary pliers is difficult and slow, as the pliers often slip off and even at the best, an even and uniform twist of the wire is seldom secured.

In concrete construction work, the forms 55 are usually held together by means of pieces

of heavy wire. A great number of loops of wire are necessary in order to hold the concrete form, and as unskilled labor is usually employed for the setting up of the forms, a great amount of time is frequently 60 wasted by the workmen, for lack of efficient tools, in twisting up the ends of the wire so as to hold the forms tightly together. With my invention, these wires may be readily twisted up in a small part of the 65 time ordinarily required for that purpose, thereby greatly facilitating the setting up of the forms.

In the construction shown in the drawings, the form shown in Figs. 1, 2, 3, 4 and 70 9 comprises a pair of semi-circular casing members 1 and 2, in the form of complementary annulus segments, adapted to form a supporting member. A pair of handles 3 and 4 are mounted on the casing members 75 1 and 2 respectively and are pivoted together, as in tongs or pliers, at 5 so that the casing members may be swung toward and away from each other.

A wire holding member of discoidal 80 shape comprising a pair of semi-circular disk segments 6 and 7, which are pivoted together at or near one side as at 8, so as to form a substantially circular disk, is journaled between the casing members 1 and 2, 85 and is adapted to rotate relatively thereto. The members 6 and 7 are provided with apertures 9 and 10 respectively, for receiving the ends or other parts of the wire to be twisted. The outer peripheral edge of the 90 wire holding member is provided with a plurality of ratchet teeth 11 which are adapted to coact with a pawl 12 pivotally mounted at 13 on the casing member 2 and which is normally urged yieldingly into contact with the ratchet teeth by means of a compression 95 spring 14, seated against the screw 14^A in the aperture 14^B. The edge of the wire holder 6—7 is flanged at 6' and 7' respectively to coact with flanges 1' and 2' on 100 members 1 and 2 (see Fig. 2), whereby said holder is positively retained in the casing 1—2 so long as the handles 3 and 4 are attached at pivot 5, and danger of separation and loss of said holder is thereby avoided. 105

The wire holding member fits somewhat loosely in the casing members 1 and 2 so that when it is turned to the position shown in Fig. 2, the members 6 and 7 may be swung apart a sufficient distance to allow the mem- 110

ber to be placed upon a pair of wires intermediate the ends thereof. The casing members 1 and 2 are normally spaced slightly apart as shown at 15 and are prevented 5 from gripping the wire holding member too tightly by means of a set screw 16 threaded through the handle 3 in position to bear against the handle 4. As the wire holding member becomes looser by reason of wear, 10 the casing members may be adjusted so as to fit closer by turning back the set screw 16.

Means are provided for positively holding the handles 3 and 4 together mechanically independent of the grip thereon by the 15 user, so that when once placed upon the wires to be twisted it can be rapidly reciprocated back and forth, which means comprises a sleeve 17 mounted loosely on the handles near their point of pivotal connection. The sleeve 17 is adapted to be slid 20 down the handles 3 and 4 as shown in dotted lines in Fig. 3. It is yieldingly retained in this position by a spring-pressed button 18 mounted in the handle 4.

25 In the construction shown in Figs. 5, 6, 7 and 8, the wire holding member comprising the disk segments 6 and 7 is provided with gear teeth 19 cut in the upstanding peripheral edge thereof, and the ratchet 30 teeth are omitted, and likewise the pawl which coacts therewith. The wire holding member is rotated relative to the supporting casing members 1 and 2 by means of a pinion 20 mounted on one end of the shaft 35 21. The shaft 21 is journaled on the bearings 22 and 23, and the other end thereof is provided with a beveled pinion 24 which coacts with a driving gear 25 journaled at 40 26 on the handle 4. A handle 27 is provided on the driving gear 25 for operating the same.

In the operation of the form shown in Figs. 1, 2, 3 and 4, the wire holding member, comprising the disk segments 6 and 7, is rotated until the point of pivotal connection 45 8 of the disks is adjacent the point of pivotal connection of the operating handles as shown in Fig. 1. The sleeve 17 is then slid down adjacent the pivot 5, and the operating handles 3 and 4 are swung apart, thereby 50 swinging the supporting casing members 1 and 2 apart and thus causing the segments 6 and 7 to open. The wire holding member, comprising the segments 6 and 7, is 55 then passed over the pair of wires to be twisted, and the operating handles 3 and 4 are brought together. The sleeve 17 is then slid down over the handles, past the spring actuated button 18 which yieldingly retains 60 it in this position. The operating handles are then reciprocated back and forth in a plane perpendicular to the axis of rotation of the wire holding member, thus causing the wire holding member to be ratcheted 65 around relative to the supporting casing

members. The pair of wires being supported in the apertures 9 and 10 are held in spaced relation and thus an even and uniform twisting of the wire is secured.

The opening and closing movements of 70 the casing 1-2 and the wire holder 6-7 are positively correlative, inasmuch as any such movement of one must be accompanied, due to their mechanical relation, by a corresponding movement of the other. The angular amplitude of such movement is inherently limited by the permanent concentricity of the coacting casing and holder segments 1, 6, and 2, 7. As the device opens and the casing segments swing apart, the holder segments slide in the casing away from the outer aperture 15, the pivot 8 remaining midway between parts 1 and 2. This movement is limited by the mutual relation of the casing and holder parts, as will be apparent, 85 but sufficient to admit the wires.

In the operation of the modification shown in Figs. 5, 6, 7 and 8, the wire is placed in the wire holding member as hereinbefore set forth. Instead of reciprocating 90 the operating handles to rotate the wire holding member, the handles are rigidly held by one hand and the handle 27 of the driving gear 25 is rotated by the other hand, thereby rotating the wire holding disk 95 through the medium of the pinion 24, shaft 21 and pinion 20.

This modification of the wire twisting tool is adapted for use in places where there is not room for reciprocating an operating 100 handle as required for the form shown in Figs. 1, 2, 3 and 4, and furthermore, a very rapid twisting of the wire can be effected by the use of the second form of the device.

Although but two specific embodiments of 105 this invention are herein shown and described, it will be understood that numerous details of the construction shown may be altered or omitted without departing from the spirit of this invention as defined by the 110 following claims.

I claim:

1. A tool comprising in combination a circular segmental casing and a flat segmental holder of less diameter carried thereby in 115 the same plane, said casing and holder being normally concentric and having means to effect relative rotation, said casing and holder each having their segments hinged together adjacent to their edges for swinging in said plane when the pivotal axes are 120 swung to their adjacent positions in radial alignment, and the coacting casing and holder segments having coacting concentric guide means adapted to maintain the concentricity of said segments in opening and closing and to prevent loss of said holder.

2. A tool comprising in combination a pair of complementary annulus segments, a pair of tong-like handles fixed to adjacent 125 130

ends of said segments and pivoted together adjacent thereto, said segments having inwardly facing channels constituting a circular raceway when said segments are closed together, a discoidal work holder carried by said segments, and means to effect rotation of said holder in said raceway, said holder comprising a pair of segments formed on their abutting edges to receive the work and pivoted together adjacent to the edge of said holder to swing in the plane thereof, said raceway being formed to maintain the concentricity of corresponding annulus and holder segments when the pivots are in adjacent radial alinement for opening and closing the tool.

3. A plier-like wire twisting tool of unitary character comprising a pair of handles connected pivotally adjacent to one end, said handles having complementary semi-circular casing members adjacent to the piv-

otal connection, and a disk-shaped peripherally flanged sectional wire holder made in two similar complementary segments hinged together at one edge and held rotatably within said casing members, said holder having a pair of wire receiving edge apertures on the line of separation where the segments abut together, ratchet means connecting operatively the holder and casing 25 adapted and arranged to facilitate rotation of the holder in the casing when said members are closed, and said casing being flanged to embrace the flange rim of said holder and overlap its inner side to maintain the concentricity of the holder and casing members when the pivots are in radial alinement and the tool is opened and closed, and so prevent removal of the holder.

Signed at Chicago this 28th day of Feb., 40
1917.

ERNST H. CARLSON.
